PAPER DISPENSER

David O. Chase and George L. Down, Skaneateles, N.Y., assignors to Hamilton Cosco, Inc., Columbus, Ind., a corporation of Indiana

Filed May 1, 1969, Ser. No. 16,969

Term of patent 14 years

Int. Cl. D6—99; D9—99

U.S. Cl. D52—2

Fig. 1

Fig. 2

FIG. 1 is a perspective view of a paper dispenser showing our new design; and

FIG. 2 is a rear elevation thereof.

The undisclosed side is a mirror image substantially the same as the side shown.

We claim:

The ornamental design for a paper dispenser, as shown and described.
